(57) **CLAIM**

The ornamental design for a kicker plate, as shown and described.

DESCRIPTION

FIG. 1 is a front perspective view of the kicker plate showing our new design.

FIG. 2 is a rear perspective view of the kicker plate of FIG. 1.

FIG. 3 is a top view of the kicker plate of FIG. 1, the bottom view being a mirror image thereof.

FIG. 4 is a right side elevation view of the kicker plate of FIG. 1, the left side elevation view being a mirror image thereof.

FIG. 5 is a front elevation view of the kicker plate of FIG. 1; and,

FIG. 6 is a rear elevation view of the kicker plate of FIG. 1.

1 Claim, 2 Drawing Sheets
